UNITED STATES PATENT OFFICE

DAVID S. BURKE, OF CLEVELAND, OHIO

OIL CAN

Application filed October 1, 1928. Serial No. 309,480.

This invention relates to metal receptacles and more particularly to a dispensing receptacle known as a hand oiler or oil can.

It often happens that when an oil can is in use the spout will become clogged with dirt or thick oil which has dried in the spout thereby making it impossible to eject oil through the spout without first removing the obstruction. This is very annoying as it is often difficult to clean the spout.

Therefore, one object of the invention is to provide an oil can which includes a cleaning stem or pin mounted in the can and extending into its spout for cleaning purposes.

Another object of the invention is to allow the spout to be slid longitudinally from an extended to a retracted position in which retracted position the cleaning stem will serve very effectively to eject through the outer end of the nozzle any substance which may have accumulated therein and clogged the nozzle.

Another object of the invention is to provide the inner end of the nozzle and the inner end portion of the cleaning stem one with a valve seat and the other with a valve adapted to have seating engagement with the valve seat when the nozzle is thrust inwardly its full extent and thereby close the inner end of the nozzle and prevent oil from leaking out of the oil can in case the oil can should be accidentally overturned when not in use. This will also serve to seal the inner end of the nozzle and prevent the oil from evaporating.

The invention is illustrated in the accompanying drawing, wherein

Figure 1 is a vertical sectional view through the improved oil can with the spout in a retracted position;

Fig. 2 is a view similar to Fig. 1 showing the spout in its extended position, and

Fig. 3 is a transverse sectional view taken on the line 3—3 of Fig. 2.

The improved oil can includes a receptacle indicated in general by the numeral 1 and having a bottom 2 and walls 3 upstanding from the margins of the bottom and terminating in a filling neck 4. The filling neck is externally threaded so that the cap

which closes the upper end of the neck may be screwed into place. This removable cap or closure 5 is formed with a centrally located opening and about the opening is disposed a threaded packing gland or neck 6 which rises from the cap 5.

The nozzle 7 is slidably passed through the opening in the cap 5 and except for its outer end portion which is tapered the nozzle is of an even diameter throughout its length so that it may be slid longitudinally through the opening without having side play. Packing 8 is provided about the nozzle within the neck or gland 6 and projects upwardly from the gland for engagement by a compressing nut or collar 9 threaded upon the neck 6. When the nut or collar 6 is loosened, the spout may be easily slid to a retracted or extended position but when the nut is tightened the packing will be compressed about the spout and firmly hold the spout in a set position. By this arrangement the spout may be moved from a retracted to a partially or fully extended position and secured in an adjusted position. It will thus be seen that the extent to which the spout projects from the can may be controlled.

In order to clean the spout, there has been provided a cleaning pin or stem 10 which is disposed vertically in the receptacle 1 and projects upwardly into the spout 7. The inner end of the stem is formed with an enlarged portion or base 11 which is of a conical shape and not only allows the stem to be firmly anchored to the bottom 2 of the receptacle but also constitutes an upwardly tapered valve adapted to fit into a tubular valve seat 12 provided at the inner end of the spout. This valve seat 12 may be formed integral with the spout but it is preferred to have the valve seat formed of lead or some other relatively soft metal and secured about the inner end of the spout. By this arrangement the valve seat projects slightly from the inner end of the spout and forms an annular shoulder adapted to contact with the inner surface of the cap 5 to limit outward movement of the spout and thereby eliminate danger of the spout being drawn outwardly too far when moved to an extended position.

Forming the valve seat of soft metal will also allow it to have snug fitting engagement about the tapered valve when the nozzle is forced inwardly and provide a very close fit between the valve seat and valve. It will thus be seen that the inner end of the spout may be tightly sealed when the spout is pressed inwardly and oil will be prevented from flowing through the spout and leaking out in case the oil can should be accidentally upset when not in use.

When the oil can is in use, the cap is removed and carries with it the spout 7. The receptacle may then be easily filled and the cap replaced. During use of the can, the spout is extended, as shown in Fig. 2, and it may be secured in an extended position by tightening the nut or collar 8. After the can has been used, the nut 8 is loosened slightly and pressure applied against the outer end of the spout to force the spout inwardly until the valve seat is disposed about the valve in snug fitting engagement therewith, as shown in Fig. 1. The nut is again tightened and the spout will be retained in its retracted position and since its inner end will be tightly closed by the valve there will be no danger of oil flowing through the spout if the oil can should be accidentally overturned. When the spout is in a retracted position, the upper end portion of the stem 10 extends through the spout to its outer end and it will serve very effectively to prevent dust from accumulating in the spout and also prevent thick oil from drying in the outer end portion of the spout and clogging the same. It should also be noted that if the outer end portion of the spout should become clogged by dirt when oiling a bearing the spout may be pressed inwardly to a retracted position and the stem will serve very effectively to eject the obstruction from the spout. I have, therefore, provided an oil can which can be easily cleaned if its nozzle should become clogged and may have the inner end of its nozzle tightly sealed in order to prevent oil leaking through the nozzle if the can should be accidentally overturned when not in use. I have also provided a can in which the effective length of the nozzle may be controlled.

Having thus described the invention, I claim:

1. An oil can comprising a receptacle open at its upper end, a removable closure for the upper end of said receptacle formed with an opening, a spout slidable through the opening in said closure and having an enlarged inner end constituting a tubular valve seat and adapted to limit outward movement of the spout by engagement with the closure, and a cleaning stem disposed vertically in said receptacle and extending upwardly through said spout and having a conical lower end portion constituting a valve adapted

to have wedging fit within the tubular valve seat and close the inner end of the spout when the spout is thrust inwardly its full extent.

2. An oil can comprising a receptacle open at its upper end, a removable closure for the upper end of said receptacle formed with an opening, a spout slidable through the opening in said closure, a valve seat at the inner end of said spout, a cleaning stem in said receptacle extending through said spout, and a valve element about the inner end portion of said stem adapted to have wedging fit within said valve seat and close the inner end of said spout when the spout is thrust inwardly.

3. An oil can comprising a receptacle open at its upper end, a removable closure for the upper end of said receptacle formed with an opening, a spout slidable through the opening in said closure, a valve seat at the inner end of said spout, a cleaning stem in said receptacle extending through said spout, and a valve element about the inner end portion of said stem adapted to engage with said valve seat and close the inner end of the spout when the spout is thrust inwardly its full extent.

4. An oil can comprising a receptacle open at its upper end, a removable closure for the upper end of said receptacle formed with an opening, a spout slidable through the opening in said closure, a tubular valve seat at the inner end of said spout formed of soft metal, and a cleaning stem disposed vertically in said receptacle and extending upwardly through said spout and having a conical lower end portion constituting a valve adapted to have wedging fit within the tubular valve seat and close the inner end of the spout when the spout is thrust inwardly its full extent.

5. An oil can comprising a receptacle having a bottom, walls, and a filling neck, a stem extending upwardly from the bottom through the filling neck and having its inner portion formed with a conical base constituting a valve, a cap removably engaged with said neck, a packing gland extending upwardly from said cap about an opening in the cap, said stem extending outwardly through the gland, and a spout slidable through the gland with the stem extending through the spout and adapted to be releasably secured in a longitudinally adjusted position by tightening the gland, said spout having its inner end portion enlarged to form a valve seat adapted to wedgingly receive the tapered inner end portion of said stem and close the inner end of the spout when the spout is thrust inwardly its full extent.

6. An oil can comprising a receptacle having a bottom, walls, and a filling neck, a stem extending upwardly from the bottom through the filling neck and having its inner portion formed with a conical base constituting a

valve, a cap removably engaged with said neck, a spout slidable through said cap with said stem extending through the spout, the inner end portion of the spout being enlarged 5 to form a valve seat serving to limit outward movement of the spout and adapted to wedgely receive the valve and close the inner end of the spout when the spout is thrust inwardly its full extent.

10 In testimony whereof I affix my signature.
